UNITED STATES PATENT OFFICE

GEORG STAUBER, OF BERLIN, GERMANY

SEAL TIGHTENING FOR CENTRIFUGAL MACHINES

Application filed October 6, 1927, Serial No. 224,495, and in Germany October 13, 1926.

In rotary or centrifugal machines appreciable clearance losses are produced between the rotating wheels and the casing. In order to reduce these losses the clearance between the wheel and casing may be reduced in a known manner as by a flexible sliding ring in order to prevent water discharge. The disadvantage of this arrangement is, however, that without exceedingly careful lubrication corrosion of the ring occurs.

A further expedient in reducing the clearance losses consists in forming one of the clearance walls in the form of a ring movable in the direction of the enlargement or reduction of the clearance space, the surface of which bordering the clearance space extends parallel to the opposite clearance wall. The movable ring under the influence of variable liquid pressure in the passage of the discharging liquid and of the counter-acting forces automatically adjusts itself to the smallest clearance opening.

The object of the present invention is to reduce the losses in a more effective way than has been possible by the devices heretofore known, and the invention consists in that the clearance walls, of which one is movable with relation to the other in the direction of the enlargement or reduction of the clearance, is so formed that the clearance cross section is continually reduced in the direction of flow of the clearance liquid. By this construction a much higher efficiency is obtained than with parallel clearances. Consequently, with the same effectiveness in operation it will be possible to adjust the clearance much more accurately and to thus maintain the water losses far less than in the case of the known arrangement of clearances with parallel walls.

In the accompanying drawing wherein the invention is illustrated the figure is a detail section showing the invention applied to use.

Referring to the drawing in detail the numeral 1 indicates the wheel, 2 the casing and 3 the clearance between them to be sealed.

The tightening is effected by a packing ring 4 which according to the invention is of a special form and by means of which the continuous reduction in the clearance space

is obtained. The form in the embodiment illustrated is such that when the counter surface at the runner is flat the side of the ring opposed to said surface is so tapered that it may only bear against the runner along a circular line so that between the ring and the runner a contracting passage 6 is formed, this form being further characterized in that between the side of the ring in front of the casing and the casing itself a pressure space 5 is provided. The spaces 5 and 6 communicate with each other and with the clearance 3 to be sealed. In the pressure space 5 there exists a substantially constant pressure dependent upon the different clearance pressures at the circumference of the clearance space 3. The pressure space 5 opposite the casing wall 2 is elastically sealed by a ring 7 surrounded by a double ring 8 of rubber or other suitable material. In the passage 6 approximately the same pressure exists as in the space 5 provided the ring 4 fits the wall 1 so closely that no water flows between them. By the contraction or reduction of the passage 6 outwardly, which is an important factor in proper packing, the pressure acting upon the tapered wall of the packing ring located on the runner side is highly variable, and in such manner that the pressure is highest when the packing ring 4 closely fits the runner 1 and steadily decreases the farther the packing ring is removed from said runner.

Since the counter pressure exerted by the liquid in the space 5 upon the ring 4 remains substantially constant, the packing ring will remain in a state of equilibrium in that position in which the pressure on the side of the clearance balances the pressure of the liquid in the space 5 and the spring forces act in the same direction where such are present.

If the packing ring 4 tends to approach the runner wheel 1, the quantity of the discharging seal water becomes less and also the discharging velocity in the passage 6 decreases. According to this action, however, the pressure in the passage 6 increases and consequently the pressure acting from the side of the clearance upon the packing ring

4 so that the packing ring is displaced from the runner.

Thus the free movability of the ring 4 is essential for the mode of operation of the device, and this ring therefore must be fastened to the casing in such manner that it may freely adjust itself in the way above set forth. As herein shown, this adjustment is permitted by suitable springs arranged on bolts loosely holding the ring 4 in attached relation to the casing 2, one of said springs being indicated at 9.

By means of the sealing device according to the invention it is not intended to produce a condition in which no water whatever discharges between the runner wheel and the packing ring. This condition would result with wear of the ring 4 and in corrosion of the flange of the wheel. It is intended, on the contrary, by shaping the packing ring 4 to enable the discharge and waste of a certain quantity of water between the runner and the packing ring, but only as much as will be necessary to obtain effective liquid lubrication between the wheel and the ring and to avoid mutual wear. This intentionally caused loss of water obviously involves a loss of energy which, however, is substantially lower than that which results with other types of sealing devices.

The load surfaces on both sides of the ring 4 are so dimensioned that the packing ring in the position of equilibrium closely approaches the runner wheel, thus permitting a slight water discharge, sufficient, however, to leave an adequate layer of lubrication between the runner and the packing ring and to prevent mutual wear of the latter.

The characteristic of the invention is the shaping of the clearance walls in such manner that a clearance contracting or decreasing in the direction of flow is formed.

I claim:

1. In a fluid pressure turbine having a casing and rotor mounted therein provided with a runner; clearance sealing means between the runner and the casing including a ring interposed between one side of the runner and the casing, the opposing side faces of the runner and the ring being spaced apart to provide a clearance passage therebetween and said ring having a single circular line of contact with the face of the runner at the outer side of said clearance passage, and means for yieldingly mounting said ring upon the casing whereby said ring is movably responsive to variable fluid pressures in the clearance passage.

2. In a fluid pressure turbine having a casing and rotor mounted therein provided with a runner; clearance sealing means between the runner and the casing including a ring interposed between one side of the runner and the casing, the opposing side faces of the runner and the ring being spaced apart to provide a clearance passage therebetween and

said ring having a single circular line of contact with the face of the runner at the outer side of said clearance passage, means for yieldingly mounting said ring upon the casing whereby said ring is movably responsive to variable fluid pressures in the clearance passage, an additional fluid pressure receiving chamber between said ring and the casing to provide a counter-pressure against the ring and equilibrate the ring in a substantially constant normal position, and means for sealing the space between the ring and the casing at the outer side of said pressure chamber.

3. A fluid pressure turbine having a casing and a rotor mounted therein provided with a runner, a sealing ring, and means for movably mounting said ring upon the casing for movement towards and from one side of the runner, the said side face of the runner and the opposing side face of the ring extending in convergent relation to each other to provide a clearance passage gradually diminishing in cross sectional area towards the discharge side of said passage, and said ring at the discharge side of the passage having a single line of circular contact with the side face of the runner, and said ring moving relative to the runner to increase the area of the clearance discharge in correspondence with increments of increase of fluid pressure in the clearance passage.

In testimony whereof I have signed my name to this specification.
